(73) Assignee: **Sy Kessler Sales, Inc.**, Dallas, TX (US)

(57) **CLAIM**
The ornamental design for a desktop apparatus for testing precious metal, as shown described.

(***) Term: **14 Years**

DESCRIPTION

(21) Appl. No.: **29/483,938**

FIG. 1 is a front perspective view of one embodiment showing our new design for a desktop apparatus for testing precious metal;

(22) Filed: **Mar. 4, 2014**

FIG. 2 is a top plan view depicting the desktop apparatus for testing precious metal shown in FIG. 1;

(51) **LOC (10) Cl.** 10-04

FIG. 3 is a bottom plan view depicting the desktop apparatus for testing precious metal shown in FIG. 1;

(52) **U.S. Cl.**

FIG. 4 is a front elevation view depicting the desktop apparatus for testing precious metal shown in FIG. 1;

USPC **D10/46**; D10/83

FIG. 5 is a rear elevation view depicting the desktop apparatus for testing precious metal shown in FIG. 1; and,

(58) **Field of Classification Search**

FIG. 6 is a left side elevation view depicting the desktop apparatus for testing precious metal shown in FIG. 1, which has left and right side symmetry.

USPC D10/46, 83; D18/7, 8
